UNITED STATES PATENT OFFICE.

EDGAR D. FELLOWS, OF BERLIN, ASSIGNOR TO THE DAVIS SEWING MACHINE COMPANY, OF WATERTOWN, NEW YORK.

CORDER FOR SEWING-MACHINES.

SPECIFICATION forming part of Letters Patent No. 250,062, dated November 29, 1881.

Application filed May 11, 1881. (No model.)

To all whom it may concern:

Be it known that I, EDGAR D. FELLOWS, of Berlin, in the county of Rensselaer and State of New York, have invented a new and useful 5 Improvement in Corders for Sewing-Machines, which improvement is fully set forth in the following specification.

This invention relates to the sewing-machine attachments known as "corders," for laying or 10 delivering a cord between or upon fabrics in position to be secured by a seam alongside of the cord, and particularly to those which have guides for folding a strip or piece of cloth, combined with a device arranged to deliver 15 the cord into the fold of the strip or piece.

Such corders have heretofore been constructed generally with a tube or eye formed in rigid or non-elastic material, and of a diameter equal to the size of the cord to be delivered, and they have been objectionable, because a separate corder has been required for each size of cord, and also because great smoothness and uniformity in the cord (when this is of proper size) have been necessary to 25 successful operation.

The present invention has for its object to obviate these objections and to produce an attachment of the kind referred to which can be used with cords of different sizes, and which 30 will inclose the cord in the folded material in the most perfect manner, notwithstanding inequalities or irregularities in said cord.

Heretofore in braiders which simply deliver a braid or cord to be stitched on by a seam through 35 the braid, and which have no folding-guide, the delivery-opening has been made adjustable to receive braid of different widths, and in some cases also a constant but yielding pressure has been exerted upon the braid by means of a 40 spring. A corder has also been devised with a tube made in two parts connected by a spring-hinge, through which the covered cord passes to the sewing-machine; and, further, in order to allow cords of different sizes to pass, the presser-foot of the machine has been provided on 45 the bottom with a groove, of which one side is formed by a plate adjustably connected with the presser-foot. In the first of these cases, however, there is no folding-guide nor cord-delivering means apart from the tube. In the 50

second, although a folding-guide is employed, there is no special means for delivering the cord into the fold made in the material by said guide, the groove in the foot not serving this purpose; and, moreover, no provision is made 55 for inequalities or enlargements in the cord. These devices, therefore, are not of the kind referred to, and to them the present invention has no reference.

The invention consists in combining with 60 the folding-guide cord-delivering means with variable opening so placed that the cord is delivered into the fold made in the material by said guide, at least one of the devices between which the variable opening is formed being in- 65 closed by the folded material.

The invention further consists in combining with the folding-guide cord-delivering means, which comprise a spring arranged to exert a yielding pressure on the cord, and also in the 70 special combination of a folding-guide and a flat spring having its end recessed or spoon-shaped, so as to partly embrace the cord.

The accompanying drawings, which form a part of this specification, illustrate corders embodying the invention. 75

Figure 1 shows in perspective a corder attached to the head of a sewing-machine. Fig. 2 is a perspective view from another position of the same corder detached from the machine, 80 and Fig. 3 an end elevation with the attaching-bar removed. Figs. 4 and 5 are perspective views, from somewhat different positions of a corder adapted to be attached to the cloth-plate of a sewing-machine, and Fig. 6 an end 85 elevation of the same. Fig. 7 is an enlarged detail view of the end of the spring which bears against the cord, and Fig. 8 a view of the spring detached.

A is a folding-guide formed of a bent piece 90 of metal with the ends turned inward, as shown at a. It is secured at one or both of said ends by soldering or otherwise to an upright plate, B, to which the end of a spring, C, is fastened by one or more screws or rivets or in any suitable way. The spring C extends through the folding-guide A, obliquely across the interior thereof, being held in that position by its own elastic force. The cord is delivered through the interior of the folding-guide and passes be- 95 100

tween the spring C and the inner wall of said guide. The free end of the spring is provided with a shallow recess, or is made spoon-shaped, (see Figs. 7 and 8,) so as to retain the cord in the middle of the folding-guide A and prevent it from escaping from the action of said spring.

Edge-guides b c are formed above and below the folding-guide, as in Figs. 1, 2, and 3, or a single guide, either above or below, can be used. In Figs. 4, 5, and 6 a lower guide only is represented. With the upper edge-guide, b, a spring-plate, e, extending over the top of the folding-guide, is employed to hold down the edge of the fabric to which the corded strip is to be attached and prevent it from escaping over the top of the edge-guide. Such a plate is not needed with the lower edge-guide, as the latter, when in use, rests upon the cloth-plate of the sewing-machine; but it can be combined also with such a guide.

If it is desired to fold the edge of a wide sheet or piece around the cord, a space for the introduction of such edge, as shown at f, Fig. 6, is left between the plate B and one of the turned-in ends of the folding-guide A.

In order to attach the corder to the machine an attaching plate or bar, D, is employed. The attaching plate, Figs. 4, 5, and 6, is or may be made in one piece with the upright plate B, and is adjustably secured to the cloth-plate of the sewing-machine by means of the thumb-screw E, which passes through the slot d. The attaching-bar, curved as shown, Figs. 1 and 2, is or may be soldered to the folding-guide, and is adjustably secured by a set-screw, g, to the hanger F, which is itself adjustably attached to the head of the machine by the set-screw G passing through a slot, h, in the upper end of the hanger.

The head and cloth-plate of a Davis sewing-machine are represented in Fig. 1; but the same means of attachment as therein shown, or means equivalent thereto, can be used with other machines.

The mode of using the corder is as follows: The attachment being adjusted in position on the machine, the strip or piece of cloth is properly introduced in the folding-guide A around the end of the spring C, and the cord is inserted between the cloth and the free end of the spring, which holds it in the fold of said cloth. The spring, therefore, not only lays the cord in contact with the cloth, but it also assists the folding operation, retaining by its pressure the cloth in proper position in the folding-guide. The spring readily yields and adapts itself to the inequalities or rough places in the cord, always maintains a gentle pressure thereon, and lays it smooth and true. When a large cord is introduced it simply pushes the free end of the spring farther to the right, Figs. 3 and 6, the delivery-opening being thus enlarged to conform to the increased size of cord to be delivered. The corder is adjusted later-

ally to bring the seam at the proper distance from the cord. The edge or edges of the fabric or fabrics to or between which the corded piece or strip is to be sewed are guided by the edge guides, or, when the corded strip is to be sewed to the fabric at a distance from the edge of the latter, the fabric is passed under or over the corder, and is guided by the operator, with or without the aid of any ordinary or suitable guides.

In the foregoing description what is regarded as the best mode of carrying the invention into effect has been explained; but various modifications may be made without departing from the spirit of said invention, and parts of the invention can be used without the others. For example, the delivering-opening for the cord, instead of being between the spring and the interior wall of the folding-guide, could be between the spring and a special support separated by a greater or less distance from said wall, or both the spring and support could be arranged outside of the folding-guide. The spring, instead of acting directly on the cord, could be made to exert its pressure through an intermediate device. The enlargement and contraction of the delivery-opening for the cord, instead of being effected automatically by the retraction and return of a spring, could be effected by a device adjustably held in position through a slot and set-screw or equivalent connection with the frame of the corder. With such an adjustable device, or with an ordinary rigid tube, eye, or groove a spring capable of yielding and adapting itself to inequalities in the size of cord could be combined. The cord could be delivered through a tube having the end split and adapted to exert a yielding pressure upon the sides of the cord.

Having now described the said invention and the manner of carrying the same into effect, what I claim is—

1. A sewing-machine corder comprising, in combination with a folding-guide, cord-delivering means with variable opening placed relatively to the folding-guide, as indicated, so that at least one of the devices between which said variable opening is formed is inclosed by the material folded by said guide, substantially as described.

2. The combination of a folding-guide and cord-delivering means, as indicated, comprising a spring arranged to exert a yielding pressure upon the cord as it is delivered, substantially as described.

3. The flat spring having its free end recessed or spoon-shaped, combined with the folding-guide, substantially as described.

In testimony whereof I have signed this specification in the presence of two subscribing witnesses.

EDGAR D. FELLOWS.
